S. M. SCHENKEIN

BOTTLE

Filed June 28, 1923

FIG. 1.

FIG. 2.

FIG. 3.

Inventor

Samuel M. Schenkein

Henry Orth

Attorney

UNITED STATES PATENT OFFICE.

SAMUEL M. SCHENKEIN, OF LYNDHURST, NEW JERSEY.

BOTTLE.

Application filed June 28, 1923. Serial No. 648,296.

To all whom it may concern:

Be it known that I, SAMUEL M. SCHENKEIN, a citizen of the United States of America, of Lyndhurst, county of Bergen, 5 State of New Jersey, United States of America, have invented certain new and useful Improvements in Bottles; and I do hereby declare the following to be a full, clear, and exact description of the invention, such 10 as will enable others skilled in the art to which it appertains to make and use the same, reference being had to the accompanying drawings, and to letters or figures of reference marked thereon, which form a part 15 of this specification:

My invention relates to bottles, more especially to perfume bottles, that may be easily and rapidly opened and closed and which will be liquid tight under all conditions when closed, so that they may be carried in a hand bag or vanity case without leaking.

To this end my invention consists in providing the bottle with a screw thread and 25 loosely mounting the stopper in a screw cap constructed to co-operate with the bottle thread and to be limited in its closing movement.

The stopper which is free to rotate as well 30 as to have longitudinal movement with respect to the cap in which it is contained and to which it is attached or connected, is urged to its seat solely by the pressure of a spring contained within and between the cap 35 and stopper.

Referring to the drawings in which like parts are similarly designated,

Figure 1 is a view partly in elevation and partly in section of the stopper seated in 40 the bottle before the cap is completely screwed down to exert spring pressure on the stopper;

Fig. 2 is a section showing the cap fully screwed down;

Fig. 3 illustrates a modification.

Referring to Figures 1 and 2, the bottle 4 has a neck 5 provided with an external screw thread 6, there being a decided shoulder 7 between the bottle and neck.

The cap 8 or rather the skirt of the cap, 50 is interiorly threaded to engage the screw threads 6, and has an internal projection or flange 9 whose central opening or perforation 10 is sufficiently large to pass the body 55 of a ground stopper 11.

The stopper plug may or may not be pro-

vided with a rod extension 12. The stopper is provided with a head 13 of larger diameter than the opening 10 in the projection of flange 9 and is thereby loosely retained 60 in the cap 8.

The customary grinding guide groove 14 may be provided between the head 13 and the stopper 11.

Within the cap and resting on the stopper 65 head 13 is a coil spring 15, held in the upper end of the cap 8 between a screw plug or closure 16 and the stopper head 13.

The cap may or may not be provided with an eye 17 loose in the cover 16 for attaching 70 a chatelaine chain, ribbon or the like.

The cap is constructed to be limited in its closing movement by having a part of it contact with the bottle and in this construction by causing the lower edge of the cap 75 skirt to strike and rest against the shoulder 7 of the bottle.

In the position shown in Fig. 1 the stopper is seated in the bottle neck but little or no pressure is exerted on it. A further partial 80 turn of the cap now seats the lower edge of the cap on the shoulder 7 of the bottle and the spring 15 exerts pressure on the stopper head and holds the stopper seated but the cap in no instance exerts pressure on the 85 head. No matter how hard the cap is screwed down only the pressure of the spring holds the stopper in place.

It will therefore not be possible to screw the cap down so hard as to burst or crack 90 the bottle or bottle neck.

In opening the bottle, should the stopper stick, the flange 9 will engage the under side of the stopper head 13 and the screw action between the cap and bottle neck will 95 furnish sufficient pressure on the under side of said head to remove the most obstinately stuck stopper.

The assembly of the device is simple. The stopper is dropped into the top of the cap, 100 the spring is then placed in and the cover 16 then screwed into place.

The cap and the stopper are thus attached to one another as a unit, and the stopper and cap are free to rotate and have longitudinal 105 movement with respect to one another.

In the modification illustrated in Fig. 3, the cap is made of sheet metal and the flange or projection is made by a crimp 9a.

In this instance the cap is not limited in 110 its movement by the lower edge of the cap skirt engaging the bottle shoulder 7, but by

the flange 9^a striking the lip of the bottle as shown. Otherwise the structure, operation and assembly of the parts is the same.

It will thus be seen that in both of the forms shown, the stopper and cap are connected and the stopper is easily removed from the bottle.

I claim—

1. A bottle stopper having a plug portion and a head extending above the plug portion, in combination with a bottle cap having means to extend under the head and between the head and plug, and a spring between the cap and head.
2. A bottle stopper having a plug portion tapered for seating in a bottle neck and a head integral with said plug extending above the plug; in combination with a bottle cap, means on the cap extending between the plug head and allowing limited independent movement of the cap with respect to said stopper, and means to permit the removal of the stopper from said cap, and a spring between said means and stopper head.
3. A bottle stopper having a plug portion and a head of larger diameter than said plug portion extending above the plug portion; in combination with a bottle cap having means to extend under the head and between the head and plug, and a spring between the cap and head.
4. A bottle stopper having a plug portion and a head extending above the plug portion; in combination with a bottle cap having means to extend under the head and between the head and plug, and a spring between the cap and head, said cap having means to engage the bottle and limit the closing movement.

5. A bottle stopper having a plug portion and an integral head extending above the plug portion; in combination with a bottle cap having means to extend under the head and between the head and plug, a spring between the cap and head and said cap having a skirt for engaging the bottle shoulder.

6. A bottle stopper having a plug portion and an integral head of larger diameter than said plug extending above the plug; in combination with a bottle cap having a projection extending and having limited movement between the head and plug, a closure for the top of the cap and a spring between the closure and head.

7. A bottle stopper having a plug portion and an integral head of larger diameter than said plug extending above the plug; in combination with a bottle cap having a threaded skirt, an annular flange in said cap extending beneath the head and between the head and plug, said plug being capable of passing through said flange, a closure for said cap and a spring arranged between said closure and head.

8. A stopper having a plug portion and an integral head of larger diameter than said plug portion; in combination with a bottle cap having a thread for engagement with a similar thread on the exterior of a bottle neck, means projecting internally of the cap extending beneath the head and between the head and plug, said plug being capable of passing said means and means between the stopper head and cap to urge the stopper to seat the plug in the bottle neck.

In testimony that I claim the foregoing as my invention, I have signed my name.

SAMUEL M. SCHENKEIN.
